UNITED STATES PATENT OFFICE.

JAMES B. BROWNRIDGE, OF TORONTO, ONTARIO, CANADA.

ANTI-RAIL-CREEPING DEVICE.

Application filed August 6, 1928. Serial No. 297,667.

My invention relates to improvements in anti-rail-creeping devices, and the object of the invention is to provide a device which will reduce to a minimum the creeping of 5 rails on rail road tracks, and in the following specification and the drawings forming part thereof, I shall describe and illustrate my invention, and a modification thereof, and what I claim as new will be set forth 10 in the claims forming part of this specification.

Fig. 1 is a plan view of the device; and Fig. 2 a front elevation thereof. Fig. 3 is a side elevation of the device showing it attached to a rail and secured to a sleeper. Fig. 4 is a view similar to Fig. 3 showing a slight modification and one of a pair of locks, and Fig. 5 is a detail showing portion 20 of the device and a corrugated surface on the underside of the bottom flange of the rail.

In the drawings, like characters of reference refer to the same parts.

At the outset it must be understood that 25 although I have illustrated and described my device as particularly adaptable to prevent the creeping of rails, it must be understood that the application of this device has a wider field, as it is found to be useful 30 in coupling together members in the construction of buildings, so as to prevent longitudinal separation thereof while construction is going on.

The device is made from a bar of metal 35 having any suitable shape in cross section, and it embraces a transverse bottom bar 2 which is adapted to be placed underneath the bottom flange 3 of the rail. Integrally formed with the said bottom bar and connected therewith each by a loop 4 are inward-upward converging sections 5, spaced apart and substantially in alignment, and connected with each section 5 by a bend 6 is a downward longitudinally-extending section 7. Each section 7 terminates in a substantially vertically-disposed loop 8. 45 9 are substantially vertically-disposed loops which are connected each with a loop 8 by a section 10, and extending from each loop 9 is a section 11, the inner ends 12 of which diverge and terminate in eyes 13.

The device is slipped on to the rail at one end, and before it has been fastened to a sleeper, the sections 11 occupy substantially the dotted position shown in Fig. 3.

In this position the bar 2 lightly rests against the underside of the flange 3, and each loop 8 rests against the upper side of said flange. The vertical flange 14 of the rail is located between the pairs of loops 8 and 9, as will be understood. When the eyes 13 are pressed into contact with a sleeper 15, and secured in this position by any suitable spike or other fastening means 16, the loops 8 in contact with the flange 3 will force the bottom bar 2 into engagement with the underside of the flange 3, and therefore since the said flange at each side of the rail will be pinched in three distinct areas or points, and since the device is attached to a sleeper, the device will operate to offer resistance to the longitudinal and lateral movement of the rail over said sleeper.

From what has been stated, it is evident 75 that the sections 11 operate as levers and the points of contact of the loops 8 with the flange 3 are the fulcrum points for the levers.

By providing the loops 9 positioned as illustrated, I increase the leverage of the sections 11 without making the device of undue length.

The diverging ends 12 of the sections 11 85 are so shaped as to avoid contact with the flange 3.

In Fig. 4 I show a modification more particularly as regards the shape of the sections 11, and show a lock 17 in the form of a wedge 90 which may be inserted between the top flange or head 18 of the rail, and the sections 11. The underside of this lock 17 will be concaved to embrace the sections 11, and the contacting surfaces of said lock and sections may be corrugated or otherwise roughened to prevent displacement of said lock. There are of course two of these locks 17, and they are forced into position after the device has been spiked or otherwise secured to the sleeper. Therefore the said locks will 95 positively prevent the withdrawal of the spikes 16, through any lifting action of the eyes 13.

To additionally couple the device to a rail or other element to be held against movement, the underside of the flange 3 may be corrugated as shown at 3', and these corrugations may be of such size as to receive the bottom bar 2.

The locks 17 are easily placed and re- 110

moved, and the careful use thereof will increase the frictional contact of the device with a rail.

While I have formed my device by bending it, I do not confine myself to any particular way of making the device.

The loops 8 and 9 are resilient portions of the device, and when the device has been secured in position, its construction is such that 10 the transverse bar 2 will be held with much force in contact with the flange 3.

Changes in form or design will readily suggest themselves to one skilled in the art, without departing from the spirit of my invention.

What I claim as my invention is:

1. An anti-rail-creeping device, embracing a transverse bottom bar adapted to rest in contact with the underside of the bottom 20 flange of a rail, and with each end of which is connected an inward-upward extending transverse section, the said sections being spaced above said bar; a longitudinally-disposed loop connected with each of the said 25 sections and located one at each side of the vertical flange of a rail, and adapted to rest in contact with the top side of said bottom flange; a lever section connected with each of the said loops, and means whereby each 30 of the said lever sections is coupled to a fixed support therefor pinching the bottom flange of said rail between said loops and said transverse bar.

2. In a device as set forth in claim 1, the provision of diverging ends for said lever sections, which diverging ends terminate in eyes to receive a suitable fastening means.

3. In a device as set forth in claim 1, the provision of additional longitudinal loops 40 extending forwardly of the first-mentioned

loops so as to increase the leverage of said lever sections.

4. In a device as set forth in claim 1, the combination of a lock in the form of a wedge adapted to be positioned between each of the 45 said lever sections and the top flange of a rail.

5. An anti-rail-creeping device, embracing a transverse bottom bar adapted to rest in contact with the underside of the bottom 50 flange of a rail, and with each end of which is connected a longitudinally-disposed vertical loop located above same and one at each side of the vertical flange of the rail, and adapted to rest in contact with the top 55 side of said bottom flange, and a lever section connected with each of the said loops and adapted to be attached to a fixed support for said rail so as to cause said bar to be held tightly against said bottom flange. 60

6. An anti-rail-creeping device having two main portions located at opposite sides of a rail, each embracing an inward-upward-extending transverse section adapted to function over the top side of the bottom flange 65 of the rail; a longitudinally-disposed loop connected with each of the said sections and located at each side of the vertical flange of the rail, and adapted to rest in contact with the top side of said bottom flange; a lever 70 section connected with each of the said loops; means extending underneath the bottom flange whereby said transverse sections are functionally associated, and means whereby each of the said lever sections is coupled to 75 a fixed support therefor thereby pinching the said bottom flange between said means and said loops.

JAMES B. BROWNRIDGE.
